UNITED STATES PATENT OFFICE.

WILLIAM H. STAKER AND NATHAN I. STAKER, OF SANDY, UTAH.

UNIVERSAL GAME BOARD.

Application filed May 18, 1923. Serial No. 639,834.

This invention relates to a game board and has for its principal object the provision of a board suitable for the playing of a great number of games although intended primarily for the playing of a game simulating base ball.

Further and important objects of the present invention lie in the provision of various details simplifying the game board and rendering more convenient the playing of various games, such details being particularly pointed out in the claims.

In the drawings illustrating the present preferred type of board embodying our invention:

Figure 1 is a general plan view of a game board.

Fig. 2 is a vertical, longitudinal section taken through one of the alleys.

Fig. 3 is a central, transverse, vertical section on line 3—3 of Figure 2 with the parts in operative playing position.

Fig. 4 is a cross sectional view of a projector which may be used with my device.

The box portion of the game board consists generally of a base 10, a rear end 11 and sides 12 and 14 together forming an open top box with a free or unobstructed front end. In the box thus formed two longitudinal partitions 15 and 16 are provided dividing the base into three sections, a fairly large major section 18 for the field portion and two equal size portions on either side thereof forming alleys 19 and 20. In order to form a convenient receptacle 21 for the various pieces and accessories a transverse partition 22 closes off the rear of the field portion forming a receptacle provided with a cover 23 and a spring catch 24.

The alleys 19 and 20 are exactly similar so a single description will suffice and the numerals apply equally well to the parts of each alley. Each alley consists of a runway 30 and a chute 31, the runway conveying the marble or other sphere 33, preferably simulating a base ball, to the pocket end of the runway where the marble drops through an opening 32 and falls to the chute returning to the player by gravity as best seen in Fig. 2. The pockets are conveniently formed by a plurality of partitions 34 here shown as five in number so that six pocket openings will be formed. The top 35 of the pockets on its forward face bears numerals shown in Fig. 3 denoting the number of the pocket opening.

The chute 31 is hinged to the rear end 11 of the board as at 36 and when used with adjustable legs hereinafter described the lower end 37 of the chute will rest on the table top 38 or other support upon which the game board is positioned. The chute is formed in any preferred manner with grooves corresponding in number to the number of pocket openings and at the lower end 60 of the chute numerals 40 are placed corresponding in position and purpose with the numerals on the face of the top 35 so that should there be any question as to which pocket opening the ball initially entered the 65 question may be definitely settled as the chute at its upper end lies so close to the runway that the marble cannot possibly get into the wrong groove or passageway.

It should be noted that the chute 31 serves 75 a double function for it not only returns the ball to the player but acts as a register or recording device. The player is confronted with numerals 1 to 6 painted above six pockets, collectively serving as a target 80 at the far end of the smooth alleyway 30, down which the player aims the ball at whichever one of the six pockets is fancied. The numerals 1 to 6 are best seen in Figure 3, and the smooth alley down which the ball 85 is aimed is best shown in Figure 2. The number of the pocket which the ball entered is accurately recorded or registered as the return apparatus 31 is not narrow or smooth, but has six grooves each being a separate 90 and distinct return runway serving exclusively its corresponding pocket. Numerals 1 to 6 are painted at the lower end 37 of the chute and can be actually seen at 95 40 in Figure 1 of the drawings.

On the field 18 is a base ball diamond 42 and with or without markings 43 denoting the positions of the players in the field but with markings 44 showing the possible positions of the players of the side 100 "at bat". Between the field and the player we preferably position a number of counting devices representing respectively the number of innings, 47; the score, 48; strikes, 49; balls, 50; and outs, 51; here shown as 105 of the abacus type, each of the abacus balls, which may also be made to represent baseballs, representing one except for the balls on the lower end of the counter 48 each of which represents five as the score may, as in the game itself, run above 10.

A sign board 60 is pivoted to the parti-

tions 15 and 16 as at 61 so that the sign board may be lowered flat against the base 10 when the game board is not in use and may be raised to 90° when the board is in position. A preferable way of holding the sign board in place is by the provision of a spring lock 63 of any of the well-known types.

A card 65 is secured to the sign board by 10 spring clips such as 66 and denotes the various possible plays with each game. Each of the cards 65 is peculiar to the particular game being played, several such cards being furnished with the game board, the card for 15 base ball, for example, containing six columns corresponding to the six pocket openings in each alley and denoting balls, strikes, hits, fouls, and all other information necessary to play the game in a manner very 20 closely imitating the actual happenings of a regularly-played game.

The board should be positioned for play in an inclined position with the edge of the board nearest the player elevated above the 25 pockets and the pockets in turn must be elevated above the ends 37 of the runways. This may be conveniently done by a pair of legs 68 and a pair of somewhat shorter legs 69 all four of which may be straight pegs 30 but at least two are preferably adjustable screw legs such as are in rather common use with toy billiard tables, the legs being shortened or extended by a turn of a knurled nut 70 in the ordinary fashion. While not at 35 all essential this improvement is extremely convenient as the greatest enjoyment may be had from the game when the board is exactly level from side to side, particularly so if the marbles are to be placed on the edge 40 75 of the runway and allowed to roll down the alley by gravity alone.

If desired the two front legs 68 may be omitted and in their stead a pair of toggle links 72 substituted, these links folding flush 45 with the base when the device is not in use and operating to support the base from the lower edge 37 of the chute when the toggle is sprung slightly beyond its central position where it engages the toggle stop as is 50 quite customary.

The method of shooting the marble down the alley may be determined at the will of the players; the ball can be placed upon the edge of the runway allowed to roll 55 slowly by gravity or the ball may be shot from the abacus end of the board in marble-shooting fashion or we may place a marble shooter or projector such as 76 on the edge of the board with its pivot directly in the 60 center of the alley and with its handle 77 extended beyond the edge of the board for convenience in manipulating it. The projectors illustrated are of well known type save for the pivot which is a small stud 79 secured to the propeller and fitting in a socket

80 in the board so they can be removed and placed in the receptacle 21 when not in use. The head 81 of the propeller is urged forwardly by a spring 82 surrounding the rod 83 and bearing against the rear edge 84 of 70 the propeller. The marble 33 is placed in the channel of the projector, the handle 77 pulled back against the tension of the spring and the device turned on its pivot 79 to aim 75 at the pocket opening desired and the ball then discharged by releasing the handle.

The central baseball field is for pictorial or visualizing purposes largely. The ball players, which are not shown in the drawing, need not be miniature human figures, 80 but can just as well be represented by "checkers" or simple disks, are moved about on the board so as to show at any moment the status of the game. All of the marble shooting is done on the two side alleys and 85 the vertical sign board 60 is used to show the moves of the game to which the player is entitled, due to his skill or lack thereof in shooting the marble into one of the six pockets that has been assigned valuable moves. 90 The central field is also of use structurally as a spacer so that the two side alleys will be sufficiently far apart to enable the two 95 contesting players to use their alleys simultaneously.

In order to specify some particular use of the device we will describe the invention in connection with the game for which the device is primarily intended, namely 100 baseball. In playing this game the checkers, pieces, or men, which preferably are small lead figures dressed in baseball costume are of two distinguishing colors representing the opposing teams. Since only four men can ever be on the bases at once there is no need to provide more than this number altho the full nine men on each side may be provided and placed in the field in their accustomed 105 positions. All of the scoring balls or markers are assembled at the right as is customary in billiards and other counting games. The player having his team in the field 110 shoots first. We will assume that he is on the left hand side of the board and the player whose team is at bat is on the right 115 hand side. The latter player moves the first ball or marker 47 to the right showing that he is playing in the first inning. As the board is actually manufactured at the present time, the balls are colored: yellow for 120 the balls 47 representing the innings, green for the upper balls 51 representing the number of men out, red for the score balls in the upper tier representing five each and blue for the balls in the lower tier 48 representing 125 one run each.

While the specific method of counting can be varied to suit it is convenient and much more exciting to design the score card so 130 the play will simulate the actual game as

closely as possible. To accomplish this the card is so made that the first player, i. e., the player whose team is in the field, discharges the marble down the left hand chute and strives to get it in the number 3 opening for that will mean a strike. The danger is that if it swerves slightly it will go into 2 or 4 which will mean the baseball is hit. We will assume that in shooting for number 3 he actually shoots it into number 2 or number 4 each of which indicate that the batter has actually connected with the ball.

The other player instantly upon seeing the marble go into the number 2 or 4 pocket may, without waiting for verification by the marble running down the inclined chute 31, discharge his marble down the right hand chute 30 in an endeavor to make the hit just registered as great as possible. He too aims for the number 3 slot for that indicates a home run after a hit. There is a danger here, too, for if he should miss the number 3 hole slightly he would get a foul (by going into number 2 or 4) and then on next shot down the left hand alley the player in the field might catch the foul and even if he did not it would be a strike in accordance with the rules of the actual game. We will assume that the player at bat misses the number 3 which counts as a home run and runs in the number 6 opening which gives him a single. This would complete the play since the securing of a single would naturally mean that the runner was safe at first base, and accordingly the player places one of his pieces at first base numbered 44 on the drawing. Players usually advance the piece slightly also to simulate the game showing that the runner is taking a "lead" off first base.

The player whose team is in the field now shoots again. There are but three things he can get from the six alleys, namely; a ball, a strike, or the fact that the batter has connected with the ball. We have described rather in detail what happens when the batter hits the ball. Should the player roll into an opening which signifies a ball, the player representing the team at bat would do nothing and this is likewise true of a strike, but on four balls or on three strikes an advance or an out is recorded.

To simplify the game as much as possible certain plays are omitted such for example as the dropping of the third strike by the catcher. The omitted plays are those occurring very rarely. In the actual game, even tho the catcher should drop the third strike, the runner is almost invariably pre-ceded to first base by the ball and is out.

The charts for the different games are printed on substantial paper or cardboard and are held in position by the clips 66. The principal chart is indicated in Figure 3 but

since it is rather complicated it is not reproduced in full. The six vertical columns represent the six openings into which the marble may go and the horizontal columns represent what the play is if the marble goes into that slot under the following conditions: single, two-base, three-base, home run, attempt to steal. The six vertical columns are actually each divided into four narrow vertical columns denoting what happens to—the man at bat, the man on first, the man on second, and the man on third and the horizontal columns are themselves divided into quite a number of contingencies, for example; bases empty, first occupied, second occupied, third occupied, first and second, first and third, second and third, and bases full. These refinements are advantageous for the very close simulation of the actual game as for example, it would never do at all to have a triple play recorded when the first man came to bat.

What we claim is:—

1. A game board employing pieces or men having a central field or game visualizing space for occupancy in various positions by men, and an independent scoring device on each side of said field, whereby the field may be used simultaneously by two rival players each scoring independently.

2. In a game board having two parallel sides and two spaced members dividing the board into a field and two runways, a plurality of pockets at the end of each runway, and a return passageway beneath each pocket.

3. In a game board, a base, an end, two parallel sides, two spaced members dividing the board into a field and two runways, a plurality of partitions at the end of each runway, and a return chute beneath each runway, each of said chutes being divided into a plurality of parallel passageways corresponding in number to the spaces formed by said partitions.

4. In a game board, a base, an end, two parallel sides, two spaced members dividing the board into a field and two runways, a plurality of partitions at the end of each runway, and a return chute pivoted to said base beneath each runway.

5. In a game board, a base, a target end, two parallel sides, two spaced members dividing the board into a field and two runways, a plurality of partitions at the target end of each runway, and a return chute pivoted to said base at the target end thereof and beneath each runway, each of said chutes being divided into a plurality of parallel passageways corresponding in number to the spaces formed by said partitions.

6. In a game board, a base, a target end, a player end, two parallel sides, two spaced members dividing the board into a field and two runways, a plurality of partitions at

- the target end of each runway, a return chute pivoted at the target end to said base beneath each runway and means for positioning the base on a table or other object
- 6 with the target end below the player end and the player end of the chute below the pivoted end whereby a marble released on either runway will roll by gravity in the space between two adjacent partitions and
- 10 will then return by gravity to the player end via one of the chute passageways.
7. In a game board, a base, a target end, a player end, two parallel sides, two spaced members dividing the board into a field and
- 15 two runways, a plurality of partitions in each runway at the target end, a return chute pivoted at the target end to said base beneath each runway, and adjustable means for positioning the base on a table or other
- 20 object with the partitioned ends below the level of the player end and the player end of the chute engaging the table, whereby a marble released on either runway will pass between a spaced member and a parallel side
- 25 and enter between two adjacent partitions and will then return by gravity to the player via one of the chute passageways.
8. A game board having a central field or score board space for the men, a return ball playing alley on each side of said field, open score pockets formed at the end of each

alley and communicating with the return member thereof, and a pivoted ball projector for each alley.

9. In a marble shooting alley, a smooth 35 unrestricted runway, a target at the rear and lower end of the runway, vertical partitions dividing the target into a plurality of pockets, and an independent return for each pocket.

10. In a marble shooting game, a plurality of spaced alleys, each having a smooth unrestricted runway, a target at the rear and lower end of the runway, vertical partitions 45 dividing the target into a plurality of pockets, and an independent return for each pocket, for indicating the pocket into which the marble was discharged, whereby a plurality of players may "shoot" their marbles simultaneously and later ascertain what 50 score a rival player has made.

11. The device of claim 10 in which there are two alleys and a baseball field is positioned between the two alleys so as to be 55 visible to both players.

12. In a baseball game, a baseball field, a scoring device at each side of the field arranged parallel and facing in the same direction and means visible to both players for indicating the value of the mark scored.
